UNITED STATES PATENT OFFICE.

FRANK D. MALTBY, OF NEW YORK, N. Y.

OSCILLATING STEAM PUMPING-ENGINE.

SPECIFICATION forming part of Letters Patent No. 293,585, dated February 12, 1884.

Application filed May 19, 1883. (No model.)

To all whom it may concern:

Be it known that I, FRANK D. MALTBY, of the city, county, and State of New York, have invented certain Improvements in Oscillating 5 Steam Pumping-Engines, of which the following is a specification.

My invention is an engine constructed, as fully described hereinafter, to secure a reciprocating rocking motion, and to reduce the difficulty of securing tight joints and avoid the complexity of ordinary constructions.

The invention further consists in a peculiar combination of engine and pumping apparatus.

15 In the drawings, Figure 1 is a sectional elevation, showing my improved engine combined with a pump. Fig. 2 is a transverse sectional elevation.

The case A of the engine also constitutes 20 the cylinder, and consists of the cylindrical body *a* and annular heads *b b'*, one of which may be fixed and the other detachable, both being flanged and recessed to form chambers receiving the packing and the followers *d*.

25 Through the heads extends a cylindrical hollow trunk, *B*, provided with a radial piston, *f*, which vibrates between two ribs or abutments, *g g'*, secured to or forming part of the case, and recessed to receive packings *e*, which prevent

30 the passage of steam between the outer face of the trunk and the edges of the abutments. The piston is likewise recessed to receive a packing, *e'*, making a tight joint between the piston and the inner surface of the cylinder. The 35 piston and abutments are preferably secured detachably and adjustably to the trunk and case, to facilitate construction and repairs. In the abutments and in the piston are channels *i*, which admit steam from the chambers

40 *x x'*, on opposite sides of the piston, to the back faces of the packings, thereby forcing the latter firmly against the bearing-surfaces, and making steam-tight joints. In the cylinder are ports *m n*, communicating with channels

45 *m' n'*, leading to a face-plate, on which slides a slide-valve, *D*, a central exhaust-port, *p*, leading to an exhaust-pipe, *o*. The valve *D* is contained within a valve-chest, *E*, to which steam is admitted, and in the chest are chambers *x x'*, receiving the opposite ends of a plunger, *J*, which is connected to the valve *D*. Channels

50 *p' q* in the chest lead from the chambers *x x'* to

the seat of a plug-valve, *G*, having two ports, *r s*, the latter always in communication with a central port, *t*, in the chest. A channel, *u*, 55 round the upper part of the valve leads to an exhaust-pipe, *u'*.

When the parts are in the position shown in Fig. 1, steam passing through the channel *n'* and port *n*, into the chamber *x'*, acting on the piston *f*, turns the trunk in the direction of its arrow until the position of the valve *D* is reversed, when the steam will pass to the channel *m'*, port *m*, and chamber *x*, and from the chamber *x'* to the exhaust through the port *n* 60 and channel *n'*. The valve *D* is thrown suddenly and then left in place by the action of the plunger *J*, which is moved by steam-pressure. Thus when the parts are in the position shown in Fig. 1, steam passes from the valve-chest through the port *t* and *s*, into the channel *q* and chamber *x'*, and throws the plunger and valve to the left. When the plug-valve *G* is turned to bring the port *r* to communicate with the channel *q*, steam is admitted from the 70 port *t*, through the port *s*, to the channel *p'* and chamber *x*, and the plunger is thrown to the right, carrying the valve *D* with it. The exhaust-steam from the chamber into which the plunger is forced escapes through the port 75 *r* and channel *u* to the escape *u'*.

Motion may be communicated to the valve *G* in any suitable manner. As shown, a lug, *v*, upon the trunk *B*, strikes an arm, *v'*, on the spindle *H*, of the valve *G*, as the piston *f* approaches the limit of its motion in either direction, the valve *G* being thus shifted positively and requiring but a slight movement, while the steam thus brought to act upon the plunger *J* shifts the valve *D* instantly and to any desired extent. 85

I do not limit myself to the use of the means described for moving the valve *D*, nor to the construction of the latter, nor to the use of a plug-valve, *G*, as a slide or other valve may 90 be used at this point.

By the construction set forth the vibration of the main piston is effected under the positive action of the steam, and with little friction, the bearing-surfaces are of such form as will 95 preserve their shapes for a long time under wear, and the packings are so arranged as to reduce wear and leakage to a minimum.

The abutments *g g'* and piston *f* are secured

detachably by means of bolts or otherwise, so that they can be readily removed and replaced and nicely adjusted.

The engine thus constructed affords special facilities for operating pumpshaving vibrating casings or pistons—for instance, such as the pump patented to Brust and Douglas, March 29, 1881, or any of a similar or analogous character—the pump being arranged, as shown, within the trunk B, with an intervening air-space, w, so as to prevent the cool pump-cylinder from condensing the steam of the engine. The cylinder or piston of the pump is connected to the trunk in any suitable manner to oscillate therewith.

I do not here claim the slide-valve and operating means, as the same will constitute the subject-matter of a separate application for Letters Patent.

20 I claim—

1. The combination of the cylindrical casing having annular heads and longitudinal abutments, a trunk projecting through the heads and carrying a radial piston, and ports

and channels and valves, and devices for operating the same from the engine to admit and exhaust the steam from opposite sides of the piston, substantially as set forth.

2. The combination of the casing, trunk, and recessed piston, and abutments fixed to the casing and trunk, and extending gradually therefrom, with packings fitting said recesses, substantially as specified.

3. The combination of the casing, oscillating trunk, open at the ends, and independent pump arranged within the trunk, and connections whereby the pump is detachably secured to the trunk, substantially as specified.

4. The combination of the casing, trunk, pump, and space w, communicating with the air, as set forth.

In testimony whereof I have signed my name to this specification in the presence of two subscribing witnesses.

FRANK D. MALTBY.
